PAUL C. DEPEW, OF CHICAGO, ILLINOIS

SPARK-PLUG.

1,266,561.

Specification of Letters Patent. Patented May 21, 1918.

Application filed June 9, 1915. Serial No. 33,006.

To all whom it may concern:

Be it known that I, PAUL C. DEPEW, a citizen of the United States, residing at Chicago, in the county of Cook and State of Illinois, have invented certain new and useful Improvements in Spark-Plugs, of which the following is a specification.

This invention relates to spark plugs to be used with internal combustion engines requiring electric ignition for explosion purposes.

One of the objects of my invention is to provide a spark plug constructed and operated so that the spark at the terminals will at all times be maintained clean, means being provided for preventing the accumulation thereon of carbon deposit.

A further object of my invention is to provide a spark plug comprising means for automatically passing air into the cylinder during the suction stroke of the piston.

A further object of my invention is to provide a simple spark plug comprising means for priming the cylinder in case of need.

In general the object of my invention is to provide a spark plug which is simple, compact and dependable, and arranged so that the spark gap terminals will be maintained clean, so that the air will be automatically admitted during the suction stroke of the cylinder, and so that the cylinder may be primed when desired. In the accompanying drawings Figure 1 is an elevation of a spark plug which embodies features of my invention; Fig. 2 is a central longitudinal section of the spark plug; Fig. 3 is an end view thereof; Fig. 4 is a central transverse section thereof; Fig. 5 is a central longitudinal section of a modified form of spark plug.

The spark plug which I illustrate in this instance as my preferred form comprises a casing 5, the casing having external threads 6 at one end, for the purpose of screwing into the casing of the cylinder in the ordinary manner, internal threads 7, and a central longitudinal passageway 8 extending the entire length of the casing. The passageway 8 is materially restricted at the lower end of the casing so as to form an aperture 9, the walls of which form the grounded terminal of the spark gap.

Threaded into the threads 7 of the upper end of the casing is the protecting casing

10. An annular insulating member 11 is fitted into the central portion of the casing and is held in place by means of the protecting casing 10, gaskets 28 preventing leakage, in an ordinary manner. The insulating member may be made of any suitable material; I prefer porcelain for the purpose.

Fixed in the member 11 is an annular member 12 having a valve seat 13 ground on the lower end thereof. This member 12 may be cast in the porcelain 11 or fixed therein in any suitable manner. A valve 14 is adapted to coact with the valve seat 13, and has a valve stem 15 projecting upwardly through member 11 and through a guide piece 16 which is fixed in the porcelain. The stem 15 is free to move longitudinally and a compression spring 17 encircles the stem, between the guide 16 and the nut 18 threaded onto the valve stem, and thus tends at all times to hold the valve 14 in contact with the seat 13. Extending downwardly from the valve 14 is a rod 19 the lower end of which forms the inner terminal 31 of the spark gap.

In operation, at the time of the suction stroke of the piston the reduced pressure in the cylinder, and hence in the chamber 29 of the passageway 8, allows the pressure of the external air to overcome the upward tendency of the spring 17 and to force the valve 14 downwardly, and thus more or less air is allowed to enter the cylinder through the passageway 30, the amount depending upon the tension of the spring 17, as controlled by the nut 18. The air passes downwardly through the chamber 29 and the opening 9, and is thus forced at a high speed against the spark gap terminals 31 and 32, blowing therefrom any particles of carbon that may have adhered thereto at the time of the last explosion. When the compression stroke occurs the gas in the cylinder is forced upwardly through the aperture 9, forcing the valve 14 closed, and at the same time forcing the gas against the spark gap terminals and tending to further clean the surfaces thereof. Finally when the explosion occurs gas is forced upwardly through the aperture 9 and then downwardly again, as the pressure in the cylinder becomes less than the pressure in the passageway 29. So that there is a continual vibration of air at high speed back and forth through the passageway 30.

and forth through the aperture 9 tending to clean the surfaces of the spark gap terminals.

Although the particular arrangement shown is not material to my invention, yet in this instance I have connected the wire 20 which leads from the magneto to the spark plug, to the upper end of the valve stem 15, immediately above the nut 18, by means of a washer 22 held firmly against the terminal 21 of the wire by a spring 23 held compressed by means of the clip 24 and nut 25. This pressure of the spring is sufficient to hold the terminal 21 in place; but it may be removed or replaced by forcing the terminal from, or in, between the nut and washer.

If it is desired to prime the cylinder, it is necessary only to pour the gasoline through the aperture 26 of the protecting casing. If desired the valve stem may then be forced downwardly, so as to allow the gasoline to pass inwardly; or the suction stroke of the piston may be depended upon to open the valve and allow the gasoline to pass inwardly. In either case the gasoline will pass downwardly and will come in contact with the surfaces of the spark gap terminals, and will assist in keeping the surfaces clean.

By the arrangement of parts shown and described it is evident that the protecting casing 10, the porcelain 11, and the inner spark gap terminals 31 may all be removed without removing the casing 5 from the cylinder; and thus all parts of the spark plug may be examined or replaced conveniently; and the external terminal 32 of the spark gap may also be cleaned as desired without removing the casing 5.

Fig. 5 illustrates a modified form of spark plug, which also embodies features of my invention. The air and gasoline inlet casting 35 is attached to the side of the casing 36 of the plug; and the valve 37 is mounted, as indicated, in the casting 35.

Although I have described with some particularity devices which embody the features of my invention, yet it is to be understood that various modifications may be made therein by those skilled in the art without departing from the spirit of my invention as indicated by the following claims.

I claim as my invention—

1. A spark plug, comprising a tube; a conductor slidably mounted in the bore of said tube; a valve fixed to said conductor; a member fixed in said tube and encircling said conductor adjacent said valve, said member having a valve seat, the walls of said seat diverging downwardly; and yielding means tending to hold said valve against

said seat, said valve arranged to open by an excess external pressure.

2. A spark plug comprising a casing; 65 said casing having a passageway therethrough; an insulation bushing surrounding the outer end of said passageway; a member mounted in said bushing, said member having a downwardly diverging valve seat on its lower end; a conductor passing through said bushing, said member and said passageway, the lower end of said conductor being adjacent to the walls of said casing; a valve fixed to said conductor below said valve 75 seat; yielding means tending to force the conductor upwardly and to hold the valve against the seat; and means for connecting an electric conductor to the upper end of said conductor.

3. A spark plug comprising a casing, said casing having a passageway therethrough, an insulation bushing in said passageway, a member mounted in said bushing and having a valve seat on its lower end, said bushing extending a material distance above said member, a conductor slidably mounted in said bushing, a valve fixed to said conductor below said valve seat, an electric conductor detachably connected to the upper 90 end of said former conductor, and means tending to force the said former conductor upwardly and to hold the valve against said seat.

4. A spark plug comprising a casing, said casing having a passageway therethrough, a member mounted in said passageway, said member having a downwardly diverging valve seat on its lower end, a conductor passing through said member and said passageway, the lower end of said conductor being adjacent the walls of said casing, a valve fixed to the said conductor below said valve seat, and yielding means tending to force the conductor upwardly and to hold the 105 valve against the seat.

5. A spark plug comprising a tube, a conductor slidably mounted in the bore of said tube, a valve fixed to said conductor, a member fixed in said tube and encircling said conductor adjacent said valve, said member having a valve seat, the walls of said valve seat diverging downwardly, and yielding means tending to hold said valve against said seat, the lower end of the bore of said tube being materially restricted, the inner surface of the said restricted lower end being formed to converge downwardly to the end opening; said valve arranged to open by an excess external pressure.

In testimony whereof, I hereunto set my hand.

PAUL C. DEPEW.
